UNITED STATES PATENT OFFICE.

EDWARD E. REICH, OF CHICAGO, ILLINOIS.

LOCKING DEVICE FOR PRESSING MACHINES.

1,425,695.

Specification of Letters Patent. Patented Aug. 15, 1922.

Application filed February 25, 1921. Serial No. 447,676.

To all whom it may concern:

Be it known that I, EDWARD E. REICH, a citizen of the United States, and a resident of the city of Chicago, county of Cook, and State of Illinois, have invented certain new and useful Improvements in Locking Devices for Pressing Machines, of which the following is a specification.

My invention relates to a locking device, 10 and more particularly to a locking device for a pressing machine, and has for its object the provision of means which will lock down the upper pressing member of such a machine upon the garment on the lower 15 pressing member.

Another object is the provision of locking means for the operating treadle of a machine.

Other objects will appear hereinafter.

The invention consists in the combinations 20 and arrangements of parts hereinafter described and claimed.

The invention will be best understood by reference to the accompanying drawings forming a part of this specification, and in 25 which,

Fig. 1 is a side view of a pressing machine with my invention applied thereto, the locking device being shown in released position.

Fig. 2 is a detailed view of the locking mechanism, showing the device in locked position.

The drawings illustrate a table 6 supported upon legs 7, which are connected by 35 brace bars 8. Brackets 9 are mounted on the table and a stationary pressing member or board 10 is fastened on said brackets, extending lengthwise of the table. A bracket 11, provided with sleeves 12, is fastened to 40 the rear edge of said table, and a shaft 13 is mounted for vertical movement in said sleeves. A supporting bar 14 is adjustably mounted on the upper end of said shaft, as by means of a set screw 15, or in any convenient manner, and an arm 16 is pivoted 45 with one end upon said bar, as at 17, and its free end is attached to and supports a pressing member or iron 18, adapted to co-operate with the pressing board 10 beneath the iron, to press garments and the like, as is well understood.

A rod 20 is pivoted with one end upon a pin 21, in a bracket 22 fastened beneath the table, and with the other end pivotally engages the lower end of the shaft 13. A collar 23 is mounted upon the intermediate

portion of said rod and a link 24 is pivotally connected with one end to said collar and the other end to an intermediate portion of a treadle lever 25, which has one end pivoted upon a bracket 26 mounted beneath the bar 8, and is provided at its other end with a foot treadle 27. A spring 28 is mounted on the bar 8 and bears beneath the collar 23, adapted to normally raise said collar and 65 iron 18, and a brace rod 29 is provided between the members 8 and 6.

The construction above described forms an ordinary construction heretofore used. To this construction I add my locking 70 means to retain the treadle lever and the pressing iron in their lowermost position. The locking mechanism comprises a ratchet bar 30 provided with ratchet teeth 31 at its lower end, which is pivoted upon the pin 75 21 of the bracket 22. A spring 32 is connected with one end to the ratchet bar and has its other end connected to the brace rod 29. A yoke 33 is mounted upon the forward end of the treadle lever and is provided 80 with an integral laterally extending pawl 34, adapted to engage the ratchet teeth 31 of the bar 30. An arm 35 provided with a hook 36 is mounted upon a pin 37 in said yoke 33, and a small pedal 38 is pivotally mounted 85 upon said pin 37 and has a spring 39 connected to it, the other end of said spring being connected to a lug 40 on the arm 35.

In operating a pressing machine with my invention attached thereto, the operator 90 steps upon the treadle 27 placing his toe upon the small pedal 38, which through the spring 39 draws the hook 36 of the arm 35 against the bar 30, engaging the ratchet teeth 31 with the pawl 34, thereby locking the 95 pedal in its depressed position and retaining the iron 18 firmly pressed down upon the garment on the board 10. The friction between the pawl and the ratchet teeth retain the members locked. To release the mechanism the operator steps upon the treadle 27, but not upon the pedal 38, whereupon the spring 32 draws the bar 30 rearward, releasing the ratchet teeth from the pawl. The spring 39 being effective merely to provide 105 a yielding connection between the pedal 38 and the arm 35. The spring 28 thereafter becomes effective to raise the rod 20, shaft 13, arms 14 and 16, and the iron 18. It is thus evident that I have provided effective 110 means to lock the treadle lever in its lowermost position and retain the iron firmly

pressed down upon the garment on the board, whereas formerly the spring 28 would become effective and raise the iron and its associated members as soon as the downward 5 stroke of the foot and treadle lever were completed.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

- 20 1. In combination with a pressing machine having a movable pressing member and an operating treadle, a bar mounted on said machine, means mounted on said treadle arranged to engage said bar and lock said treadle and movable member in position, and means mounted on said engaging means for embracing said bar and bringing it and said engaging means in locking position.
- 25 2. In combination with a pressing machine having a movable pressing member and an operating treadle to operate said member, a ratchet bar depending from said machine, a pawl mounted on said treadle to engage said bar, means mounted on said pawl for embracing said bar, and means mounted on said pawl and connected to said embracing means for bringing said bar and pawl in locking engagement.
- 30 3. In a machine having an operating treadle; a holding member mounted on said machine, means mounted on said treadle to engage said holding member and hold said treadle in position, means for embracing said holding member, and means connected to said embracing means for moving said holding member and its engaging means into locking position.
- 35 4. In a machine having an operating treadle, a ratchet bar mounted on said ma-

chine, pawl means mounted on said treadle 50 to engage said bar and lock said treadle in position, means mounted on said pawl means for engaging said bar, and means mounted on said pawl and connected to said engaging means for bringing said pawl and bar into 55 locking position.

5. In a machine having an operating treadle, a ratchet bar mounted on said machine, pawl means mounted on said treadle to engage said ratchet bar and lock said 60 treadle in position, means mounted on said pawl means for embracing said bar to engage it with the pawl means, and resilient means to normally retain said pawl and bar in released position.

6. In a machine having an operating treadle, a ratchet bar mounted on said machine, a yoke mounted on said treadle, a pawl extending from said yoke, an arm mounted on said yoke and embracing said bar, and means to operate said arm to bring said bar and pawl into locking position.

7. In a machine having an operating treadle, a bar movably mounted on said machine, a yoke mounted on said treadle, a 75 member extending from said yoke, an arm movably mounted on said yoke and embracing said bar, and a member pivoted on said yoke and connected with said arm for bringing said bar and said extending member into 80 locking position.

8. In a machine having an operating treadle, a ratchet bar mounted on said machine, a yoke mounted on said treadle, and a pawl extending from said yoke, an arm 85 mounted on said yoke and embracing said bar, means to operate said arm to bring said bar and said pawl into locking position, and means for automatically releasing said bar from said pawl when said treadle is de- 90 pressed.

In testimony whereof I have signed my name to this specification in the presence of two subscribing witnesses.

EDWARD E. REICH.
